LUDWIG P. KONGSTED, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

SIGNAL HORN.

Application filed June 4, 1925. Serial No. 34,816.

In signal horns, particularly intended for automotive vehicles and the like, it is often desirable to produce a warning signal that is startling by reason of its high pitch or ringing tone. This has been done in some measure by means of a rigid disc fastened centrally of a diaphragm that is vibrated by an electromagnet, but the mass and therefore the mechanical inertia of the vibrating parts are thus increased and also the likelihood of the diaphragm to crack or break where it bends within its clamped peripheral rim. Furthermore, by reason of the rigid connection between the diaphragm and the disc, the two vibrate synchronously at all times and thereby do not so effectively produce the overtones or the high pitch desirable for warning signals.

In accordance with my invention, two or more sound waves of different frequencies or out of time phase with one another, one or more of the sound waves preferably having overtones, are generated to produce a signal of ringing character capable of extreme penetration and startling effect over great distances. To do this, there may be a plurality of independently supported diaphragms which have different natural periods of vibration or are so located relatively that upon simultaneous vibration there is produced a resultant tone made up of fundamental notes and overtones, and also beats if desired, at least one of these diaphragms preferably being a resilient member consisting either of a resilient diaphragm or a rigid member spring-supported to increase the effect. Or, any means, such as a siren mechanism or a reed, may be used to pulsate a column of air which acts on a diaphragm, preferably a resilient member, to set it into vibration of its own natural period which may be different from the frequency of the air column. I prefer to pulsate the air column by a diagram that is electromagnetically or mechanically vibrated at high frequency, and also to use an independently-supported resilient member which substantially but not quite fills the diameter of the sound chamber of the first diaphragm so as to provide a comparatively narrow annulus of open space for the uninterrupted passage of a small section of the pulsating air column while at the same time absorbing sufficient energy from that column to be effectively set into vibration thereby. The two trains of sound waves so generated are then combined in the horn conduit or other form of sound outlet which is thus open to the diaphragm and also to the resilient member.

In the embodiment in which the independently-supported resilient member comprises a rigid member supported by a resilient member or a spring spider fastened to the rigid member and to the casing, some of the energy of vibration of the rigid member may be transmitted to the casing itself; thereby resulting in the generation of additional sound waves in the outside air directly from the sides of the casing. These sound waves in the radiate in a direction different from the waves emanating from the mouth of the conduit and also partially combine therewith in the production of the warning signal.

In the accompanying drawings illustrating my invention in application, as an example, to an electromagnetic horn, Fig. 1 is a central longitudinal section, partly in elevation; Fig. 2 is a section on line 2—2 of Fig. 1; and Fig. 3 shows the resilient member in front elevation.

The housing consists of a pressed-metal portion 1, a pressed-metal intermediate portion 2 fastened thereto and clamping the diaphragm 3 and forming the sound chamber 4, and a drawn or rolled steel sound conduit 5 fastened with its neck in telescoped relation to the spout 6 of the intermediate portion. An electromagnet, having its winding 7 around the middle leg of the T-shaped laminations 8 and electrically connected through the spring-pressed mechanical interrupter 9 to a suitable source of current such as a 6-volt storage battery (not shown), actuates a laminated armature 10 to which is rigidly fastened the diaphragm 3 and the push rod 11. The diaphragm 3 is so tensioned as to normally hold the armature 10 away from the poles of the electromagnet and the push rod 11 away from the deflectable lever of the interrupter 9, but when an operating switch (not shown) in the supply circuit is closed, current flowing through the winding 7 causes the attraction of the armature 10 toward the poles of the electromagnet until the interrupter 9 is opened. The armature is then pulled back by the diaphragm until the interrupter closes, whereupon the action is rapidly re-

peated until the operating switch is released by the operator.

The vibration of the diaphragm 3 causes a pulsation of the air column in the sound chamber 4. A large part of that air column gives up its energy in acting upon the disc 12, which is made of a light rigid material as aluminum or magnesium and which is fastened centrally by the riveted stud and nut 13 to a spring spider 14. Since this spider is riveted at 15 to the housing, the disc 12 is then free to vibrate independently of the diaphragm 3 and therefore, upon being vibrated by the air column intercepted by it, generates sound waves of a frequency that may be different from those generated by the diaphragm 3, depending upon the natural period of vibration of the disc 12 with its spring support 14. Owing to this spring mounting, overtones as well as fundamental notes are generated by the disc 12. However, the ringing character of the signal so produced is increased by reason of the fact that the sound waves generated by that part of the diaphragm 3 opposite the free annular space between the housing portion 2 and the rim of the disc 12 pass by the disc and combine in the conduit 5 with the sound waves generated by the disc. The result is the production of a signal having fundamental tones and overtones, and beats if desired, that give a startling signal of a ringing and penetrating character particularly effective for vehicles. It is obvious that the tone may be varied by changing the longitudinal separation of the disc 12 and diaphragm 3, and the diameter of the disc 12, and also by cupping or otherwise changing the shape or the natural period of vibration of the disc 12 with its spring 14 forming the resilient member.

As a result of the connection of the spider 14 to the diaphragm 12 and the portion 2 forming a part of the casing, some of the energy of vibration of the diaphragm 12 is transmitted directly to the casing which then generates additional sound waves that radiate from the casing in a direction different from that of the waves from the mouth of the conduit 5.

Having thus described my invention, what I claim is:

1. In a signal horn, a plurality of vibratile diaphragms independently supported for vibration at individual frequencies, means for simultaneously vibrating said diaphragms, and a sound outlet open to said diaphragms for combining the sound waves produced thereby into a resultant warning signal.

2. In a signal horn, a plurality of vibratile diaphragms independently supported for vibration at individual frequencies having different natural periods of vibration, means for simultaneously vibrating said dia-

phragms, and a sound outlet open to said diaphragms for combining the sound waves produced thereby into a resultant warning signal.

3. In a signal horn, a plurality of vibratile diaphragms of which at least one is a resilient member, said diaphragms being independently supported for vibration at individual frequencies, means for simultaneously vibrating said diaphragms, and a sound outlet open to said diaphragms for combining the sound waves produced thereby into a resultant warning signal.

4. In a signal horn, a sound chamber, a plurality of vibratile diaphragms independently-supported in said sound chamber for vibration at individual frequencies, means for simultaneously vibrating said diaphragms, and a sound outlet open to said diaphragms for combining the sound waves produced thereby into a resultant warning signal.

5. In a signal horn, a vibratile diaphragm, means for vibrating said vibratile diaphragm to produce pulsations of an air column, a second vibratile diaphragm mounted independently of the first for vibration at its natural frequency and arranged to be vibrated by the pulsating air column produced by the vibration of the first diaphragm, and a sound outlet open to both diaphragms for combining the sound waves produced thereby into a resultant warning signal.

6. In a signal horn, a diaphragm, means for vibrating said diaphragm to produce pulsations of an air column, and a second diaphragm mounted independently of the first diaphragm in the sound chamber thereof, the second diaphragm substantially but not quite filling the diameter of the sound chamber.

7. In a signal horn, means for pulsating an air column, an independently-supported member interposed in the path of the air column so as to be vibrated thereby at its natural frequency, and a sound outlet open to said pulsating air column and also to said member for combining sound waves of the air column and of the member into a resultant warning signal.

8. In a signal horn, means for pulsating an air column, and a spring-supported rigid member interposed in the path of the air column so as to be vibrated thereby.

9. In a signal horn, a vibratile diaphragm, means for vibrating said diaphragm, a sound conduit, a member located in the conduit and supported independently of the diaphragm for vibration at its natural frequency, and a sound outlet open to the diaphragm and also to said member for combining the sound waves produced thereby into a resultant warning signal.

10. In a signal horn, a sound conduit, a

- vibratile diaphragm peripherally supported by the conduit, means for vibrating said diaphragm, a member located in the conduit and supported thereby, and a sound outlet 5 in air communication with the diaphragm and also with the member for combining the sound waves produced thereby into a resultant warning signal.
11. In a signal horn, a diaphragm, means 10 for vibrating the diaphragm, a sound conduit, and a spring-supported rigid member located in the conduit and supported independently of the diaphragm.
12. In a signal horn, a vibratile dia- 15 phragm, means for vibrating said dia- phragm, a sound chamber in front of the diaphragm, a member located in the sound chamber and supported independently of said diaphragm for vibration at its natural frequency, and a sound outlet open to said diaphragm and also to said member for combining the sound waves produced thereby 20 into a resultant warning signal.
13. In a signal horn, a diaphragm, means for vibrating the diaphragm, a sound chamber in front of the diaphragm, a sound conduit leading from the sound chamber, and a rigid disc spring-supported in the sound chamber independently of the diaphragm, 25 said disc having a diameter less than that of the sound chamber but greater than that of the neck of the conduit.
14. In a signal horn, a casing, means for pulsating an air column within the casing, a rigid member interposed in the path of the 30 air column so as to be vibrated thereby, and a resilient support fastened to the rigid member and to the casing.
15. In a signal horn, a casing, a dia- 35 phragm in the casing, means for vibrating said diaphragm, a rigid disc in front of said diaphragm, and a spring spider fastened centrally of the disc and to the casing.

In testimony whereof I affix my signature.

LUDWIG P. KONGSTED.

- vibratile diaphragm peripherally supported by the conduit, means for vibrating said diaphragm, a member located in the conduit and supported thereby, and a sound outlet 5 in air communication with the diaphragm and also with the member for combining the sound waves produced thereby into a resultant warning signal.
11. In a signal horn, a diaphragm, means 10 for vibrating the diaphragm, a sound conduit, and a spring-supported rigid member located in the conduit and supported independently of the diaphragm.
12. In a signal horn, a vibratile dia- 15 phragm, means for vibrating said dia- phragm, a sound chamber in front of the diaphragm, a member located in the sound chamber and supported independently of said diaphragm for vibration at its natural 20 frequency, and a sound outlet open to said diaphragm and also to said member for combining the sound waves produced thereby into a resultant warning signal.
13. In a signal horn, a diaphragm, means 25 for vibrating the diaphragm, a sound chamber in front of the diaphragm, a sound conduit leading from the sound chamber, and a rigid disc spring-supported in the sound chamber independently of the diaphragm, 30 said disc having a diameter less than that of the sound chamber but greater than that of the neck of the conduit.
14. In a signal horn, a casing, means for pulsating an air column within the casing, 35 a rigid member interposed in the path of the air column so as to be vibrated thereby, and a resilient support fastened to the rigid member and to the casing.
15. In a signal horn, a casing, a dia- 40 phragm in the casing, means for vibrating said diaphragm, a rigid disc in front of said diaphragm, and a spring spider fastened centrally of the disc and to the casing.

In testimony whereof I affix my signature.

LUDWIG P. KONGSTED.

Certificate of Correction.

It is hereby certified that in Letters Patent No. 1,608,218, granted November 23, 1926, upon the application of Ludwig P. Kongsted, of Springfield, Massachusetts, for an improvement in "Signal Horns," errors appear in the printed specification requiring correction as follows: Page 1, line 44, for the word "diagram" read *diaphragm*; line 62, for the misspelled word "resilient" read *resilient*; line 70, strike out the words "in the," and line 90, for "T-shaped" read *E-shaped*; and that the said Letters Patent should be read with these corrections therein that the same may conform to the record of the case in the Patent Office.

Signed and sealed this 28th day of December, A. D. 1926.

[SEAL.]
